UNITED STATES PATENT OFFICE.

JULIAN E. CORBIN, OF ALAMEDA, CALIFORNIA.

DOOR-HANGER.

1,303,775.

Specification of Letters Patent. Patented May 13, 1919.

Application filed June 6, 1918. Serial No. 238,790.

To all whom it may concern:

Be it known that I, JULIAN E. CORBIN, a citizen of the United States, residing at Alameda, in the county of Alameda and State 5 of California, have invented certain new and useful Improvements in Door-Hangers, of which the following is a specification.

This invention relates to improvements in hangers and more particularly to a device 10 for mounting sliding doors, windows and like closures.

The principal objects of the invention are to provide a device which permits the easy 15 operation of the closure, which is simple in construction and which is noiseless in operation.

With these and other objects in view, the invention consists of certain novel features of construction, combinations and arrangements of parts hereinafter described and more specifically pointed out in the appended 20 claims; it being understood that changes in form, proportion, size and minor details of construction within the scope of the 25 claims may be resorted to without departing from the spirit of the invention or sacrificing any of the advantages thereof.

Referring to the drawings forming a part of the specification,

30 Figure 1, is a view in side elevation showing a door in its closed position and the manner in which my improved hanger is attached thereto.

Fig. 2, is a corresponding view of the door 35 partly opened.

Fig. 3, is a view in end elevation.

Fig. 4, is an enlarged sectional view on the line 4—4, Fig. 1. Fig. 5, is a view in modified form of my invention.

40 Referring to corresponding parts in the several views by the same numerals of reference, 1 denotes a door or other horizontally movable closure which is adapted to move across the opening 30, and into a pocket 45 formed on one side thereof. Above this opening is a longitudinal recess 31 on the sides of which are the supporting members 2. Attached to the adjacent faces of these members are a pair of parallel rails to which 50 are pivotally attached certain link members hereinafter described. These rails may be of any preferred form and attached to the supporting structure in the most convenient manner.

55 Likewise the hanger is attached to the door in any preferred way which may vary

with different conditions. As here illustrated, to the top edge of the door is attached a longitudinal strip 5 to each side of which are clamped rails 4 which are higher 60 than strip 5 thus forming a slot in which various links hereinafter mentioned are positioned. The strip 5 is attached to the top of the door by screws 6 and the rails 4 to strip 5 by screws 7.

65 Pivots attached to the rails 3 and 4 is a pair of links 8 and 12 each of the same length and having their other ends pivotally attached to each other and to a bar 10 as shown at 32. A similar pair of links 9 and 13 have their lower ends pivotally connected to the rails 3 and 4, respectively, and their outer ends to each other, and to the other end of bar 10 as at 33. The length of bar 10 is equal to the distance between the lower 75 pivotal points of the parallel links 8—9 or 12—13. The links 8 and 9 are preferably formed of two parts with the lower ends connected to the opposite rails 3.

75 Pivots attached to the rails 3 and 4, respectively, is a third pair of links 14 and 15 which are of equal length and disposed so that angular relation between them is always different from the angular relation between the pair 8—12 or 9—13. These 85 links 14 and 15 are placed between the aforesaid mentioned pair in order to economize in length and they have their outer ends pivotally attached as at 34. The length of these two members is such that when the 90 door with the attached members 4 moves in a horizontal direction, the axis of the pivot 34 will describe substantially an arc of a circle.

95 On the pivot 32 which joins the links 8, 12 and the bar 10, is mounted a connecting member 16 and on the pivot 34 to which the links 14 and 15 are attached is mounted a shorter connecting member 17 the outer end of which is pivotally connected to the 100 outer end of member 16 as at 36. The length of these two members is such that when the door with the attached members 4 moves in a horizontal direction, the axis of the pivot 36 will describe substantially an arc of a 105 circle.

On the pivot 36 are also mounted links 21 the length of which is that of the radius of the arc just mentioned and which have their lower ends pivotally attached to the 110 member 3 at the center of this arc. Thus by causing the pivot point 36, by means of

links 21, to move in the arc which it describes when the door is moved horizontally, the latter will move horizontally when the hanger is operated. It will be noted that 5 when the angle between the links 14—15 is obtuse, the links 8—12 and 9—21 are at an acute angle. On the other hand, when the door is moved a sufficient distance to make an obtuse angle between the links 8—12, 10 then the links 14—15 will be at a lesser angle. This construction enables me to obtain the greatest practical movement of the door for a given length of levers as in no case are all the links so flattened out that 15 excessive strain is produced in the parts.

The door itself, is maintained in a horizontal position by means of the parallel levers 9 and 13, 8 and 12 and by the further pair of levers 14 and 15. Thus when the 20 door is moved toward the left the various levers assume the position shown in Fig. 2 and to all intents and purposes the door moves in a horizontal direction. In this construction but little head room is required in order 25 to gain a large door opening and the latter will move quietly and easily and there are no parts to become out of order or rollers to jump out of their coöperating track or grooves. The weight of the door is uniformly distributed over a number of pivotal bearings which therefore do not readily 30 become out of order.

As the links which constitute the pairs 8—12, 9—13 and 14—15 are of equal length 35 and the lower pivotal points are in the same plane it will be apparent that each of these pairs always form an isosceles triangle and that the pivotal points 32—33 and 34 will move half the distance that the door travels 40 and therefore each moves the same horizontal distance. Hence, the links 16—17—21 constrain the points 32—34 to move equal distances for a given horizontal movement of the door and maintain the required relation 45 between the pairs of links that the latter will support the door and cause it to move in a horizontal direction.

Furthermore by locating the lower pivotal point of link 21 out of the center of the arc 50 above described, the door can be made to slightly rise or fall toward the end of its travel to the lift and can therefore be made self-closing or self-opening.

In the modified form shown in Fig. 5, instead of providing a pair of parallel connected links to prevent a pendulum-like movement of the door, I provide two independent sets of links arranged one adjacent each side of the door. In this arrangement, 55 links 50 and 54, corresponding to links 12 and 15 of the main form, are pivotally attached to the door while links 52, 53 and 55 corresponding to links 8, 14 and 21, respectively, have their lower ends attached to 60 frame 51. Links 50 and 52 have their upper

ends pivotally connected to each other and to the connecting link 56. Links 53 and 54 have their upper ends pivotally connected to each other and to the short link 57, while the other end of links 55, 56 and 57 are pivotally connected at a common point. 70

While I have shown and described the preferred embodiments of my invention, it will be understood that I do not confine myself to these arrangements but wish to cover such 75 modifications as are embraced within the scope of the claims.

I claim as new and wish to cover by Letters Patent:—

1. A hanger comprising in combination 80 with a door and its frame, two pairs of links, one link of each pair being pivotally attached to said door and one end of the other link of each pair to said frame, and the outer ends of said links of each pair being pivotally attached to each other, a connecting bar pivotally attached to the outer ends of said pairs of links, a third pair of links connected to said door and said frame and having their outer ends pivotally connected, a pair 85 of links pivotally connected at one end and having the opposite end of one of the links pivotally attached to the pivot of one of said first mentioned pairs of links and having the opposite end of the other link pivotally attached to the pivot point of said third pair 90 of links, and a link pivotally attached to the pivot point of said last mentioned links and to said frame. 95

2. A hanger comprising in combination 100 with a door and its frame, two pairs of parallel links, the links of each pair being pivotally connected on their outer ends and the other ends of parallel link of each pair being connected to said door and said frame, a third pair of links pivotally connected on their outer ends and to said door and said frame on their other ends, and a system of three links, pivotally connected at a common 105 point and having their other ends connected to said frame, to the outer end of one of said first and said last mentioned pair of links. 110

3. A hanger comprising in combination 115 with a closure and its frame, two pairs of links, the links of each pair being of equal length, means pivotally connecting the ends of one link of each pair to said frame and the ends of the other link of each pair to said closure, means pivotally connecting the other ends of said link of each pairs to each other, a system of three links each having one end pivotally connected on a common center, and means connecting the other end of one of said last mentioned links to said frame and one end of each of the other of said last 120 mentioned links to one of the pivotally connected ends of said pairs of links. 125

4. A hanger comprising in combination 130 with a closure and its frame, a pair of links pivotally connected at one end and having

the other ends pivotally connected to said closure and said frame, a second pair of links pivotally connected at one end and having the other end of one link pivotally attached to said closure adjacent the point where the link of said first mentioned pair is attached, means attaching the end of the other link of said last mentioned pair to said frame, said links being attached to each other 5 so as to form unequal angles therebetween, a connecting link pivotally attached to each pair where they are joined to each other, a link having one end attached to said frame and the other end pivotally attached to the 10 15 ends of said connecting links.

5. A hanger comprising in combination

with a door and its frame, two pairs of parallel links, the links of each pair being pivotally connected on their outer ends and the other ends of parallel link of each pair being 20 connected to said door and said frame, a third pair of links pivotally connected on their outer ends and to said door and said frame on their other ends, and forming an unequal angle with the aforesaid pairs, and 25 a system of three links pivotally connected at a common point and having their other ends connected to said frame, to the outer end of one of said first and said last mentioned pair of links.

In testimony whereof I affix my signature.

JULIAN E. CORBIN.
